UNITED STATES PATENT OFFICE

165,886

NECKTIE RACK

Roland B. Thompson, Lincoln, Nebr.

Application November 5, 1951, Serial No. 17,277

Term of patent 14 years

(Cl. D33—8)

To all whom it may concern:

Be it known that I, Roland B. Thompson, a citizen of the United States of America, residing at the city of Lincoln, county of Lancaster, State of Nebraska, have invented a new, original, and ornamental Design for a Necktie Rack, of which the following is a specification, reference being had to the accompanying drawing, forming a part thereof, and wherein:

Figure 1 is a top plan view of a necktie rack illustrating my new design.

Figure 2 is a side elevational view of the necktie rack shown in Figure 1.

Figure 3 is an end elevational view of the necktie rack shown in Figure 2 and taken from the left-hand side of the latter figure.

I claim:

The ornamental design for a necktie rack, as shown.

ROLAND B. THOMPSON.
